UNITED STATES PATENT OFFICE.

ERNEST R. UHLIN, OF WHITTIER, CALIFORNIA.

GAS AND STEAM CONVERTIBLE ENGINE.

No. 893,557.

Specification of Letters Patent.

Patented July 14, 1908.

Application filed June 26, 1905. Serial No. 267,026.

To all whom it may concern:

Be it known that I, ERNEST R. UHLIN, a citizen of the United States, residing at Whittier, in the county of Los Angeles and 5 State of California, have invented new and useful Improvements in Gas and Steam Convertible Engines, of which the following is a specification.

The object of my invention is to provide a 10 new and improved convertible engine and more particularly a convertible gas and steam engine of the two-cycle gas-engine and double acting steam-engine type. This class of engine is now extensively used in drilling 15 and operating oil and gas-wells, and my invention is designed to provide a cheaper and more efficient engine of this class than those heretofore in use and also to provide a construction whereby the engine may be 20 more quickly converted from a steam-engine into a gas-engine and vice versa.

In the accompanying drawings which illustrate an application of my invention, Figure 1, is a side elevational view partly in section 25 of an engine embodying my invention; Fig. 2 a central horizontal sectional view taken on line 2—2 of Fig. 1; Fig. 3, a view similar to Fig. 1, taken from the opposite side of cylinder; Fig. 4, a part elevational and a part sectional view the section being taken on line 4—4 of Fig. 1; Fig. 5, a detail sectional view taken on line 5—5 of Figs. 1 and 3; Fig. 6, a section taken on line 6—6 of Fig. 1; Fig. 7 a section on line 7—7 of Fig. 2; Fig. 8 a section 30 taken on line 8—8 of Fig. 2; Fig. 9, a plan detail view of cap; and Fig. 10 a section of cap taken on line 10—10 of Fig. 9.

Referring to the drawings, 1 designates the cylinder having a water-jacket space 2, and 3 40 a piston dividing the interior of the cylinder into chambers 4 and 5. Attached to and closing one end of the cylinder is a hollow-head 6; this head is in communication with a steam-chest 7 by fluid-passages 8 and 8^a. 45 As illustrated passage 8^a is formed in the head and said head is further provided with a valve 9 for controlling the passage of fluid from the chest to one end of the cylinder. Located in the steam-chest and designed to 50 operate as is usual in double-acting steam-engines, is a slide-valve 10 having a valve-stem 11. Steam is admitted to the compression or opposite end of the cylinder from the chest by way of passage 12, cap 13, and passage 14. Steam exhaust passage 15 is controlled by the slide-valve as is usual in this

class of engines. Passage 15 communicates with discharge nozzle or opening 16.

A characteristic and important feature of the present invention is that the gas-exhaust 60 from the ports 17, unites with the steam-exhaust, and I am enabled to employ a single discharge 16 for both the steam and gas-exhausts, this construction greatly simplifies and cheapens the cost of this class of engines. 65

In addition to the parts above mentioned I employ an explosive-mixture compression-chamber 18, as illustrated and as preferred chamber 18 is in the form of an annular chamber partly surrounding the cylinder and is 70 formed between an inner wall 19 and the inner surface of the outer wall of the cylinder. 20, designates the explosive mixture intake-ports, these ports being in communication with a gas and air mixing chamber 21, and 75 the latter chamber is in turn in communication with an air inlet 22, and with a gas-inlet 23. The explosive-mixture drawn into chamber 4 through intake-ports 20 uncovered by the piston, passes from chamber 4 80 through passage 14, cap 13 to the compression-chamber 18, and after being compressed in said chamber is permitted to enter the explosive end of the cylinder, by way of governor valve 25, chamber 24, and ports 85 24^a. The explosive mixture is again compressed by the return stroke of the piston. The subsequent operations in the cycle are similar to the usual operations of a three-port two-cycle gas engine. 90

When using the explosive-mixture hollow-cap 13 is turned so that its solid part 13^a, covers passage 12 leading to the steam-chest, thereby preventing the explosive-mixture passing to the steam-chest. This turning of 95 cap 13 as just described, brings its passages 13^b in such a position as to allow the explosive-mixture to pass through the cap to the compression-chamber or jacket 18. While gas is being used communication between the explosive end of this cylinder and the steam chest is cut off by means of valve 9. Steam enters mixing chamber 21 through ports 20 after slide valve 10 has discontinued admitting steam. Steam entering chamber 100 21 is therefore in the form of exhaust and during said operation the exhaust pressure at air inlet 22 is above atmospheric pressure, consequently the air and gas cannot enter openings 22 and 23, and as the gas supply 110 pipe will be provided with a check-valve the steam exhaust cannot enter said supply pipe.

While running on steam both openings 22 and 16 will serve as steam exhaust-outlets.

Assuming the engine to be running with steam as the motive-fluid and it is desired to 5 change to gas; this may be accomplished without stopping the engine by means of the following operations: After releasing the clutch pulley, not shown, shut off the steam at throttle-valve, not shown, but which is 10 located on top of the steam-chest; then turn cap 13 so that solid part 13^a covers steam-passage 12. As the turning of cap 13 only takes an instant the momentum of the fly-wheel keeps engine running while the cap is 15 being adjusted. After this is accomplished steam is again admitted to the steam-chest and from thence to the explosive-end of cylinder through the opening in valve 9. The engine is now admitting steam to one end 20 only of the cylinder and when run in this manner a few revolutions will expel all vapors from chamber 4 or the front of cylinder. Vapors are expelled from chamber 4 by 25 being passed through steam passage 14, valve 13, governor valve 25, chamber 24, and through port 24^a into chamber 5 where the pressure has been relieved by the opening of port 17 by the piston. The piston having 30 uncovered said ports an instant before uncovering port 24^a. After the engine has run a few moments air and gas are admitted 35 through the intake ports 20 after which steam is again shut off on top of this steam-chest, and valve 9 turned to close the steam-inlet passage leading to the explosive-chamber. The engine now being converted into 40 an explosive two-cycle engine will continue to operate as such until it is desired to change the same back into a double-acting steam-engine.

Particular attention is called to the fact that I dispense with the usual intake-valve or air and gas-valves, and, when running on gas there are no moving parts in or connected with the cylinder except the piston and governor.

What I claim is:

1. In a gas and steam convertible engine, the combination with a cylinder provided 50 with explosive mixture intake and exhaust-ports, of a piston controlling said ports, a steam-chest, steam-passages leading from the chest to opposite ends of the cylinder, a

steam exhaust-passage, an annular explosive mixture compression-chamber partly surrounding the cylinder, said cylinder having inlet-ports 24^a, a chamber 24, and a valve 25, a cap-valve for closing the steam-passage leading to one end of the cylinder and adapted to direct the explosive-mixture from the 60 intake-ports to said compression-chamber, a valve for closing the other steam-passage, and a common main exhaust-outlet in communication with the explosive-mixture exhaust-ports and the steam exhaust-passage. 65

2. In a gas and steam convertible engine, the combination with a cylinder provided with explosive mixture intake and exhaust-ports, of a piston controlling said ports, a steam-chest, steam-passage 12, passage 14, a 70 ported cap provided with ports adapted to be brought into communication with said passages, an annular explosive mixture compression-chamber partly surrounding the cylinder, said cylinder having inlet-ports 24^a, 75 chamber 24, a valve 25, said ported cap adapted to be turned in one direction to register with a port leading to the compression-chamber and with passage 14 leading to the intake-ports and to shut off steam from the 80 chest to one end of the cylinder, and turned in the opposite direction to close communication between the intake-ports and the compression-chamber.

3. In a gas and steam convertible engine, 85 the combination with a cylinder provided with explosive-mixture intake and exhaust-ports, of a piston controlling said ports, a steam-chest, steam-passages from the chest to opposite ends of the cylinder, a steam exhaust-passage, a common main exhaust outlet in communication with the explosive-mixture exhaust-ports and the steam exhaust-passage, an annular compression-chamber, said cylinder having ports 24^a, chamber 90 24, a valve 25 a ported cap provided with means to shut off steam from the steam-chest to one end of the cylinder and to direct the explosive mixture from the intake-ports to the compression-chamber. 95

In testimony whereof I affix my signature, in presence of two subscribing witnesses.

100 ERNEST R. UHLIN.
